UNITED STATES PATENT OFFICE.

HARRY E. HOWARD, OF CHICAGO, ILLINOIS.

CURTAIN-STRETCHER.

SPECIFICATION forming part of Letters Patent No. 699,685, dated May 13, 1902.

Application filed December 23, 1901. Serial No. 86,883. (No model.)

To all whom it may concern:

Be it known that I, HARRY E. HOWARD, a citizen of the United States, residing at Chicago, in the county of Cook and State of Illinois, 5 have invented certain new and useful Improvements in Curtain-Stretchers; and I do hereby declare the following to be a full, clear, and exact description of the invention, such as will enable others skilled in the art to which 10 it appertains to make and use the same.

My invention relates to improvements in the side bars and attaching-pins of curtain-stretcher frames or devices commonly used for drying washed lace and other fabric curtains, so that they will dry quickly and without shrinkage or distortion.

The object of my improvements is to provide a curtain-stretcher side bar having an open slot extending longitudinally therethrough, 20 so formed that it may be cheaply manufactured, possess maximum strength and durability, and furnish a suitable bearing for the attaching-pins used in conjunction therewith; also to provide an adjustable pin 25 adapted to engage and securely hold the curtain and so formed that it will transmit the strain or tension exerted upon it by the stretched curtain directly against the front wall of the slotted portion of the bar, such 30 strain being first distributed uniformly on the base of the pin instead of on one side or edge of such base, as in other devices of a similar character.

A further object is to provide an attaching-pin having its point so formed that it will 35 present an acute angle at the portion engaging the fabric of the curtain, whereby it will prevent the latter from slipping off the point of the pin through the movement of the curtain by the wind or otherwise and will resist 40 the tendency of the pin to bend down or outwardly, to which vertical pins are liable.

An additional object is to furnish a pin which may be readily grasped by the fingers 45 in moving it back and forth in the slot, thus permitting quick and easy movement or adjustment without twisting the base in the slot and without danger of pricking the fingers.

Another object is to provide a pin which 50 will bear frictionally against the bar when not in use, so that it will not slide out of posi-

tion, but when subjected to slight strain may be laterally adjusted.

Having the foregoing special objects and others of economy and general utility in mind, 55 I have designed the device shown in the accompanying drawings, which form a part of this application, and in which—

Figure 1 is a perspective view of a curtain-stretcher side bar (in part) provided with my 60 improvements. Fig. 2 is a cross-section of the same. Fig. 3 is a perspective view of the preferred form of my improved attaching-pin, and Fig. 4 is a perspective view of a modified 65 form of pin.

Referring to the drawings in detail, A represents a section of a wood side bar of a stretcher-frame which is provided with an open vertical slot a^2 , extending longitudinally therethrough near one edge, which is rabbed to form an extension a' on its lower side and an overhanging flange a^3 on the upper side of said edge. The slot-opening a^4 extends between the extension and the flange. It will be noted that the slot a^2 is parallel 70 with the front edge of the bar, thus bringing it at right angles to the line of strain, which is horizontal, as indicated by the broken line $x x$ in Fig. 2.

The attaching-pin, which forms a part of 80 this invention, is formed of a single piece of wire bent to form a base B of rectangular contour, also bent to form a cross-bar or portion b' , extending inwardly to the center of the base, a portion b^2 extending outwardly 85 and downwardly and a portion b^3 bent upwardly and inwardly at an acute angle with the part b^2 and terminating in a sharp point.

The several bends necessary to form the parts b' , b^2 , and b^3 are at such angles that 90 when the curtain is placed over the part b^3 and stretched to the opposite side bar the strain will be exerted on a plane substantially horizontal to the center of the base of the pin, thus distributing the tension as near as 95 may be equally throughout such base, and thereby causing the latter to bear uniformly against the front wall of the slot. The maintenance of the tension in a horizontal plane is provided in part by the shape of the pin 100 and in part by the extension a' , on the upper side of which bears the outer or hook por-

tion of the pin. It is obvious that when the curtain is placed over the point of the pin and drawn taut the fabric will be drawn down into the acute angle between the point and 5 the part b^2 and that the inclination of the point will prevent the accidental displacement or removal of the curtain at such point.

To provide against the too free movement of the pin through the slot when the frame is 10 not in use, I cause the bend between the parts b' and b^2 to frictionally engage the lower edge of the flange a^3 , as shown in Fig. 3; but when pull is exerted on the outer portion of the pin this bend will become flattened sufficiently to permit the lateral adjustment of 15 the pin in the slot.

In the modified form of pin shown in Fig. 4 I extend the part b' entirely across the center of the base of the pin and bend it back 20 upon itself for half of its length before forming the part b^2 ; but in other respects the pin is the same as shown in the other figures. This modified form adds somewhat to the 25 strength of the device and serves to more effectually distribute the strain equally on the base of the pin.

In devices of the kind herein described heretofore patented, so far as I am aware, the form and arrangement of the slots or grooves 30 in the bars and the form and arrangement of the attaching-pins have been such that the strain has been exerted on one side wall of the slot and usually in a plane across the grain of the wood, as indicated by broken lines y 35 and z in Fig. 2, thus making easy the breaking of said wall or walls. In some of these devices the pins are tilted when under strain with a view of making them bind in the slot or groove; but in my invention strain 40 on the pins causes them to be relieved from binding in the slots, does not tilt the base of the pins, but causes it to bear against but one wall of the slot. As the adjustment of the

pins is made before the curtain is attached, it is important to have the pins remain in 45 their adjusted positions until the curtain is hooked thereby, and this I provide by the frictional engagement between the parts b^2 and a^3 in the manner described.

While I do not claim that the strain on the 50 pin will be distributed with exact uniformity throughout its base, such will be the effect, in a substantial degree, of the construction and arrangement set forth.

Having thus described my invention, what 55 I claim as new, and desire to secure by Letters Patent, is—

1. In a curtain-stretcher, a bar having an open vertical slot extending longitudinally therethrough, an attaching-pin formed of a 60 single piece of wire bent to form a base portion adapted to slidingly fit said slot in the bar, bent to form an upwardly-projecting hump between the point and the base, said hump adapted to frictionally engage one of 65 the walls of the slot, and said pin also bent to form an acute-angled hook, the angle of which is substantially in the same plane as the center of the base portion, substantially in the manner and for the purpose described. 70

2. In a curtain-stretcher, a stretcher-bar having a narrow vertical slot extending therethrough near one edge, and with an extension on the lower side of said edge and a stretcher-pin having a base fitting said slot, 75 and provided with a bend adapted to engage the portion of the bar overhanging said slot, and having a hook portion adapted to engage an extension on the lower side of the edge of the bar, substantially as set forth. 80

In testimony whereof I affix my signature in presence of two witnesses.

HARRY E. HOWARD.
